Incorporated, Memphis, Tenn., a corporation of
Tennessee

Application May 15, 1933, Serial No. 671,172

16 Claims. (Cl. 19—44)

This invention has general reference to means and methods for separating and segregating fibrous or other light materials from heavier matter; but specific reference will be made herein 5 to apparatus and a method especially adapted for separating and segregating cotton fibers from the hulls of decorticated cotton seeds.

In the machines and methods heretofore devised for effecting such separation and segregation 10 as is contemplated in connection with the present invention, the raw or combined materials are fed into a closed vertical drum; are threshed or beaten by a large number of horizontally-disposed beaters or thresher arms; the fiber or 15 lint is drawn upward by means of a fan, and discharged from the upper portion of the beater drum; and the delinted hulls and other heavy foreign matter fall from the drum, through openings at the bottom thereof. Due to defects 20 in the designs and methods of operation of all of the heretofore-known machines with which the present applicants are familiar, each thereof comprises an excessive number of parts; is usually of unnecessary height; is overly sensitive, 25 and varies in the grade of output; and is unduly expensive as to first cost, maintenance, and power required for operation.

The theory upon which the designs and methods of operation of prior defibrating apparatus 30 seemingly were based, was that special provision must be made to prevent the intake of air into the separation chamber through the chute or other form of passageway by which raw material must be conducted to the separation chamber, and that 35 in the endeavor to prevent withdrawal from such chamber of hulls or the delinted hulls, combined or in company with the fiber or lint, the separation chamber must either be of very considerable height, or water-jacketed. This, however, 40 was only partially successful, since if the supply of hulls ceased or diminished for any reason, and the machine therefore was not fully charged, a considerable portion of the hull bran was drawn over with the fiber.

The present applicants, however, have proceeded upon, and by practical use have verified the correctness of, the theory that air may be admitted to the passageway through which the 45 raw material is delivered to the separation chamber; that the extent and manner of applying air to such raw material during the defibrating process has important bearing upon the efficiency, output, and operating power required for the defibrating apparatus; and that, if suitably

designed, a very low separating and segregating chamber may be employed.

The primary object of the present invention is to improve upon the means and methods for defibrating and segregation known heretofore, and to overcome the objections thereto, particularly in the following respects:

By providing a defibrating and segregating apparatus in which the raw material will be sucked upward by a fan toward the center of the separator drum, and the heaviest of the foreign matter, such as stones or pieces of metal, will not enter said drum, and therefore will not come into contact with the beaters or other parts that might be damaged thereby.

By providing such an apparatus in which an ample supply of air will be supplied to the beater drum, in such a way that, without interference with the thoroughness of the defibrating action, the power required for operation of the device 10 will be minimized, and its output capacity will be magnified.

By providing such an apparatus in which a small number of horizontal arms, each terminating in a vertically-disposed, removable beater blade, will be employed in place of the relatively large number of horizontal beaters used heretofore.

By providing such an apparatus having a deflector above and closely adjacent to the beater arms, so that air currents will be diverted toward the beater blades, and the defibrating and segregating efficiency of the apparatus will be promoted.

By providing such an apparatus having deflectors depending from its top, near the outlet for fiber, to prevent portions of the hulls or defibrated hulls from being drawn out with the lint or fiber.

By providing such an apparatus having a ribbed or otherwise roughened inner surface, either integral with the beater drum or constituting a lining therefor; such surface being in such position that the raw material will be rubbed against it by the beater blades.

By providing a method of defibrating in which the raw material fed into the separation chamber will be deflected toward the inner peripheral surface thereof before being threshed or beaten; will be rubbed against said surface while air is 50 being drawn upward through said material; and the lighter material will be further deflected and drawn out of said chamber at the top by such upward air current, while the heavier material will pass therefrom by gravity.

The means by which the foregoing and other desirable objects are accomplished by our present invention, and the manner of their accomplishment, readily may be understood from the following description on reference to the accompanying drawings, in which:

Fig. 1 is a central sectional elevation of an apparatus illustrative of a preferred form of the invention, in which the material to be defibrated is delivered to the separation chamber at the bottom thereof.

Fig. 2 is an elevation of the same.

Fig. 3 is a sectional plan, the section being taken substantially on line III--III of Fig. 1.

Fig. 4 is a central sectional elevation of an alternate form of the apparatus, in which the material to be defibrated is delivered to the separation chamber at the top thereof.

Fig. 5 is a sectional plan, the section being taken substantially on line V--V of Fig. 4.

Referring now to the drawings in detail, and first considering the form of the apparatus illustrated in Figs. 1, 2 and 3, the reference numeral 10 designates a shallow cylindrical drum, hereininafter also referred to as the separation chamber, having a roughened interior surface, which preferably is provided by a removable liner 11 of heavy, small-mesh wire screen or a mechanical equivalent thereof. If preferred, however, such interior surface may be vertically ribbed, corrugated, knurled, or otherwise roughened. Said drum is provided with flanges or brackets 12, by which it is supported upon suitable foundations 13.

The removable top cover 14 of the drum or chamber 10 is in the form of an annular plate, from which depends an annular baffle or curtain 15, concentric with, and definitely spaced from the inner periphery of, said drum. At the central opening in said cover, is an upwardly-extending flue 17, communicating with a cylindrical, closed chamber 18 which houses a suction fan 19. The blades of said fan are mounted upon, and are rotatable with, a vertical shaft 20, disposed centrally of the flue 17. Within and concentric with said flue, and depending from the bottom of the fan chamber 18, is an annular baffle or curtain 21.

The vertical shaft 20 extends downward through the separation chamber 10, and is connected, as by any preferred form of coupling 22, with the shaft 23 of a motor 24. The upper end of the frame of said motor is reduced in size to form an annular shoulder 25. Supported on and extending upwardly from the shoulder, is a cylindrical member which terminates in an annular, horizontal leg 27 that is concentric with, but definitely spaced away from the inner periphery of, the separation chamber 10. Extending completely around the interior of said chamber, between its lower flange 28 and the annular leg 27, is an annular screen 29, which may be formed either of a perforated plate or of heavy wire mesh, and which is secured to the flange 28 and to the leg 27 of the collar 26. A hopper 30 may be supported from flange 28 and leg 27, below the screen 29, so that material passing through said screen will fall into said hopper; and chutes 31 discharge such material at opposite sides of the motor 24.

Rotatable with the vertical shaft 20, and disposed substantially at the middle of the separation chamber 10, are a plurality of beater arms 32 (a desirable number has been found in practice to be four). Said arms lie in the same horizontal plane, and may either be unitary with or re-

movably secured to a plate or spider 33 forming part of the sleeve 34 which is keyed upon, or otherwise secured to, the shaft 20. At the end of each of said arms, and removably secured thereto, as by bolts and nuts 35, is a vertically-disposed beater blade 36. The length of said arms is such as to position said blades closely adjacent the interior surface of the separation chamber 10, and beyond the outer surface of the annular baffle or curtain 15. At the upper side 10 of the arms 32, and either secured thereto or directly to the shaft 20, is a circular plate 31, preferably of somewhat less diameter than the interior of the annular baffle or curtain 15.

The chute 38, through which the material to be defibrated is delivered to the separation chamber 10, is provided with a feeder 39, which may be of any preferred type, and which, since it forms no part of the present invention, is merely indicated conventionally. Below said feeder, an extension 40 of said chute extends below the separation chamber 10, and is curved so as to communicate with said chamber through the bottom thereof, and to discharge toward the center of said chamber. At a point preferably in the substantially-vertical portion of the chute-extension 40, is an opening 41, and within said extension, at said opening, is a baffle 42 for deflecting the hulls through said opening. Hulls so deflected are drawn in by air entering the opening 41 below such baffle, or are delivered upon a platform 43, which preferably has a skirtboard extending around its three sides, from which platform they are drawn in by the air. A slide 44 extends somewhat above the platform 43 at the opening 41 and is vertically movable to vary the extent of its projection thereabove, and/or the size of said opening. Heavy foreign matter, such as stones or pieces of metal, is deposited upon the platform 43, and does not pass 40 therefrom into the separation chamber, where its presence would be harmful to the lining 11, the blades 36, and other parts.

In the alternate form of the apparatus, as shown in Figs. 4 and 5, the fan casing 18A is placed at one side of the center line of the separation chamber 10, and communicates through a lateral flue 45 with a vertical flue 46 which leads from said chamber centrally thereof, and preferably extends a sufficient distance thereto to form an annular baffle or curtain 47. Said fan is driven, through the medium of a pulley 48, from a counter shaft or other source of power (not shown). The shaft 49, by which the beater arms are rotated, may be similarly driven, as through the medium of a pulley 50.

In said alternate form, the material to be defibrated is delivered, through a chute 38 and a chute extension 40A, into the separation chamber 10, at the top thereof. An air-admission opening 51 is formed in the horizontal leg 27A which extends outward from the cylindrical member 26, said opening preferably being disposed diametrically opposite the chute extension 40A, and being intended for much the same purposes as the openings 41 and 42 shown in Fig. 1. In both the preferred form and the alternate form, the hopper 30 has an upper portion which underlies all of the separation chamber 10.

From the foregoing description, the operation 70 of our improved defibrating apparatus, and its adaptability for accomplishing all of the desirable objects recited hereinbefore, readily may be understood. In its preferred form, as illustrated in Figs. 1, 2 and 3, the cotton seed hulls 75

are delivered, at a substantially uniform rate, by the feeder 39, into the chute-extension 40, are deflected by the baffle 42 therein, and any heavy foreign matter, such as stones or pieces of metal, 5 is deposited upon the platform 43. The suction created by the fan 19 draws the hulls with attached lint into the separation chamber 10, where the deflector plate 37 causes it to be diverted outwardly in all directions toward the liner 11 of said chamber, and thus into the path 10 of the beater blades 36. The action of said blades in beating said material and rubbing it against the rough-surfaced liner 11, loosens and separates the fiber or lint from the hulls and/or other foreign matter, and leaves the lint free to be drawn through the flues 17 and 21 into the fan casing 18, whence it may be discharged into a storage receptacle, transporting means, or the like (not shown). 15

20 In its passage from the chamber 10 into the flue leading to the fan, the lint or fiber is deflected by the depending curtain 15 and the curtain formed by the flue 21, and any hull bran that may be combined with or accompany the 25 lint or fiber is thus detached therefrom, and drops back into chamber 10, whence it falls, with the other delinted hull material, through the mesh openings in the annular screen 29 into the hopper 30, and is discharged through the chutes 31.

30 It will be understood that this machine as above described is one that has been built for delinting cotton seed hulls. Cotton after picking, is passed through gins which remove the bulk of the lint from the seed, but leave short 35 lint or fiber adhering to the seed. These seed are then cut or broken and the meats shaken out, leaving the hulls as thin curved pieces having lint attached to one side. This then is the material which is above described as being treated. With the lint attached it is easily carried by air currents, during treatment the hull is broken into smaller fragments which, freed from lint, drop by gravity from the air current. 40

45 In order that the operation of any defibrating apparatus may be commercially satisfactory, the resulting fiber must be free from hulls or other foreign matter in the fiber produced, such as would remain therein if the fiber were removed directly from the separation chamber in a rapidly moving air current. And yet, the strength of the suction created by the fan is an important factor in determining the rate of fiber output of such apparatus. By the present invention, provision is made for meeting the first 50 of the foregoing requirements by the use of the deflector plate 37 and the baffles formed by the curtain 15 and the flue 21, so that the raw material cannot be drawn into the flue 17 before it is acted upon by the beater blades 36, and the 55 separated fiber must pass under the baffle or curtain 15 before it can enter the flue 17, and any hull bran combined with or accompanying the fiber is thus deflected and caused to drop back into the chamber 10. It is found however that there is a tendency of the lint to pack around the shaft of the machine and interfere with the operation of the device. To obviate this, an auxiliary supply of air is admitted as close as 60 possible to the shaft. In Fig. 1 this auxiliary air is supplied through the intake feed chute, which discharges well inward from the supply entering through the outlet screens 29, and in Fig. 4 through the openings 51, likewise inward 65 from these screens. The rate of output of apparatus embodying the present invention is far greater, and the power required for operating it much less, than those of any defibrating apparatus of similar form heretofore known to the present applicants, this being due partly to the use of the vertically-disposed beater blades 36 5 but even more to the special provisions for admitting an ample and distributed supply of air to the separation chamber, and rapidly withdrawing the separated fiber therefrom, in such 10 a way as not to interfere with thorough defibration and segregation.

15 The operation of the alternate form of the apparatus, as illustrated in Figs. 4 and 5, differs in two respects from that just described. In said alternate form the raw material is delivered to the separation chamber at the top thereof; and the separated fiber is carried a greater distance, and both vertically and horizontally, to the fan casing. It is contemplated 20 that, to facilitate installation and operation in certain forms of existing structures, and in connection with certain arrangements of other apparatus, it might be found desirable to employ such alternate form of delivery, and/or such 25 alternate arrangement of the fan and the flues leading thereto.

30 Various modifications of minor details of the herein-described defibrating means and method doubtless readily will occur to those skilled in this art, and we therefore do not desire to have our invention construed as being limited to any details not specifically claimed.

35 Having now fully disclosed the invention, what is claimed is:

1. In apparatus for defibrating cotton seed hulls, a vertical shaft and beaters secured to and extending radially therefrom, a shallow chamber concentric with said shaft and housing said beaters, an exhaust fan, said chamber having an annular cover and a lint flue leading from the opening in said cover and to said fan, a baffle concentric with said shaft and depending from said cover, and a disk concentric with said shaft, of greater diameter than said flue, and disposed below and spaced from said cover. 40

2. In apparatus for defibrating cotton seed hulls, the combination, with a shallow upright drum having an annular cover, and having a bottom comprising an annular screen portion adjacent the drum wall, and a closed central portion, of a feed chute leading to said drum, a vertical shaft extending into the drum, beaters carried by said shaft, an exhaust fan, a central lint flue leading from said annular top and to said fan, and baffles within said drum, including a horizontally-disposed disk extending radially beyond said flue, and a cylindrical curtain wall extending downward from said top. 50

55 3. In defibrating apparatus, a cylindrical chamber of restricted height, having an annular top and a bottom comprising a central closed portion and a screen portion extending therefrom to the wall of the drum; a feed chute leading into said drum; means for admitting air through the bottom of said drum; an exhaust fan; a lint flue leading from the opening in said top and to said fan; a vertical shaft extending centrally into said drum; beater arms carried by said shaft and radiating therefrom, each of said arms carrying a vertically-disposed blade; an annular baffle depending from said top and housing the upper ends of said blades; a second annular baffle depending from said top and lying radially inward from said first baffle; 60

65

70

75

and a cylindrical disk carried by said beater arms and extending radially beyond said flue.

4. In defibrating apparatus, a vertical shaft having beaters secured to and extending radially therefrom; a chamber around said shaft and beaters; an exhaust fan; said chamber having a bottom and an annular cover, and said bottom having screened openings therethrough; a lint flue leading from said cover to said fan; a baffle concentric with said shaft and of greater diameter than said flue, projecting into said chamber; and a feed chute having its lower end curved inwardly and upwardly into said bottom, said chute having an air inlet thereinto.

15. 5. In apparatus for defibrating cotton seed hulls, the combination, with an upright drum having an annular cover, and having a bottom comprising an annular screened portion adjacent the drum wall and a closed central portion, 20 of a vertical shaft extending through said bottom into the drum; beaters carried by said shaft; an exhaust fan; and a feed chute including a portion curving inwardly and upwardly into the bottom of said drum, said chute having a trapped 25 opening for the discharge of heavy foreign material.

6. In defibrating apparatus, a cylindrical chamber having an annular top, and having a bottom comprising a closed central portion and 30 a screened portion extending therefrom to the wall of the chamber; a feed chute leading into said chamber; means for introducing air into the lower portion of said chamber; an exhaust fan; a lint flue leading from said top to said fan; a vertical shaft extending into said chamber; beaters carried by said shaft and radiating therefrom; 35 annular baffles depending within said chamber; and a cylindrical disk carried by said beaters, the diameter of said disk being proportioned relatively to said annular baffles.

7. In apparatus for defibrating cotton seed hulls, the combination, with a cylinder having an annular cover, a bottom comprising an annular screened portion adjacent the cylinder wall, and 45 a closed central portion, of a feed chute leading into said cylinder, air being admitted to said cylinder through said chute; a vertical shaft extending through said bottom into the cylinder; beaters carried by said shaft; an exhaust fan; a lint flue leading from said top to said fan; baffles within said cylinder; and means for introducing an auxiliary supply of air into said cylinder through the bottom thereof.

8. In defibrating apparatus, a cylindrical chamber having an annular top, and having a bottom comprising a central closed portion and 55 a screened portion extending therefrom to the wall of the chamber; a feed chute leading into said chamber; means for introducing air into the bottom portion of said chamber; an exhaust fan; a lint flue leading from said top to said fan; a vertical shaft extending into said chamber; beater arms carried by said shaft and radiating therefrom, each of said arms carrying a vertically-disposed blade; an annular baffle depending from 60 said top, and housing the upper ends of said blades; a second baffle depending from said top, and lying radially inward from said first-named baffle; and a cylindrical disk carried by said beater arms, and extending radially beyond said last-named baffle.

9. In defibrating apparatus, a vertical shaft; beaters secured thereto and extending radially therefrom; a cylindrical chamber housing said beaters, said chamber having a bottom and an

annular cover; an exhaust fan; a lint flue leading from said cover to said fan; spaced baffles substantially concentric with said shaft, depending within said chamber and flue; a circular disk substantially concentric with said shaft, and of greater diameter than the smaller of said spaced baffles, disposed intermediate the height of said chamber; means for feeding material into said chamber; and screened openings through said chamber bottom to permit discharge of the heavier portions of the material therethrough.

10. In apparatus for defibrating cotton seed hulls or the like, the combination with a vertical casing sealed against lateral inflow of air, having a bottom head apertured immediately adjacent said casing for discharge of defibrated hulls and ingress of air, both along the vertical wall line of said casing and below the zone of beating action, means for supplying hulls into said casing, and means for beating such hulls against 20 said casing to dislodge fiber therefrom, of means establishing an upwardly moving current of air through said apertured head and along the interior of the wall of said casing, opposing egress of hulls through said apertured head, said head being additionally apertured radially inward remote from the zone of beating action for ingress of an auxiliary air supply for lint transference.

11. In apparatus for defibrating cotton seed hulls or the like, the combination with a vertical 30 casing having a bottom head apertured adjacent said casing for discharge of defibrated hulls and ingress of air, means for supplying hulls into said casing, and means for beating such hulls against said casing to dislodge fiber therefrom, of means 35 establishing an upwardly moving current of air through said apertured head and along the interior of the wall of said casing opposing egress of hulls through said apertured head, said head being additionally apertured radially inward from 40 the zone of beating action for ingress of an auxiliary air supply for lint transference, and means for baffling direct flow of said latter air.

12. In apparatus for defibrating cotton seed hulls or the like, the combination, with a stationary vertical casing having a substantially imperforate cylindrical wall, and a bottom head, an annular portion of which head adjacent said wall is perforated, of means for supplying hulls to said casing, means for baffling upward movement 50 along the axis of said casing, means for threshing said hulls against said wall, and means for passing air in a vertical direction through said perforated portion of said head and upward in the threshing zone to remove the separated fiber.

13. In apparatus for defibrating cotton seed hulls or the like, the combination, with a stationary vertical casing substantially cylindrical, and having a bottom head, an annular portion of which head, adjacent said casing is perforated, 60 of means for supplying hulls to said casing, means for impeding vertical movement of said hulls along the axis of said casing, and for deflecting said hulls laterally across such perforated portion, means for beating said hulls against said casing wall, means for passing a vertically-directed air current upward through said perforated portion and along said casing to remove separated fiber, and means above said impeding means for baffling radially inward flow of said air 70 current.

14. In apparatus for defibrating cotton seed hulls or the like, the combination with a stationary vertical casing having a bottom head apertured adjacent said casing for discharge of de- 75

fibrated hulls and ingress of air, means for supplying hulls to said casing, and means for deflecting hulls toward said casing and beating them thereagainst to detach fiber therefrom, of 5 means for establishing flow of air through said apertured head into said casing and upward therethrough, in the zone of said beating action, and means for impeding radially inward flow of such current from said beating zone.

- 10 15. In a defibrating apparatus for cotton seed hulls, or the like, a treatment chamber, a feed chute leading thereto, and means for separating heavy foreign matter from said hulls, said chute including a section discharging by gravity, 15 said section having a discharge opening at one side thereof and an inclined baffle terminating said section at said opening, a horizontally disposed, open top receptacle below said baffle and opening and adapted to receive discharge from 20 said section, said chute having an entrance opening leading laterally thereto below said baffle

and above the adjacent top of said receptacle, and means for causing a hull-conveying air current to said chute through said opening, whereby to deflect said hulls into and reclaim and carry said hulls into, said chute while allowing heavy foreign matter to drop and remain in said receptacle. 5

16. A method of defibrating cotton seed hulls or the like, which comprises subjecting the hulls to a threshing action in a vertically disposed zone 10 shielded against radially inward airflow, to loosen the fiber therefrom in the presence solely of a current of air introduced below and moving upward into and along the zone of threshing action and promoting separation of the lint from the 15 heavier hull portions thereof, and supplementing such action with a remote air current radially inward from the threshing zone to accomplish removal of the lint. 15

CAREW HENRY REYNELL. 20
ARTHUR J. V. WARE.
